[57] CLAIM

The ornamental design for a bottle carrier, as shown and described.

DESCRIPTION

FIG. 1 is a perspective view of a bottle carrier;
FIG. 2 is a front elevational view thereof;
FIG. 3 is a right side elevational view thereof, the left side
view being a mirror image;
FIG. 4 is a top plan view thereof;
FIG. 5 is a bottom plan view thereof; and,
FIG. 6 is another perspective view thereof, shown in an
in-use position.
The broken lines shown in FIG. 6 are for illustrative
purposes only and forms no part of the claimed design.
